UNITED STATES PATENT OFFICE.

ALLYN B. WALTON, OF LORAIN, OHIO.

DESIGN FOR A LIGHTING FIXTURE.

Application filed February 26, 1924. Serial No. 8,741. Term of patent 3½ years.

To all whom it may concern:

Be it known that I, ALLYN B. WALTON, a citizen of the United States, residing at Lorain, in the county of Lorain and State of Ohio, have invented a new, original, and ornamental Design for Lighting Fixtures, of which the following is a specification, reference being had to the accompanying drawing, forming part thereof.

In the drawing, Figure 1 is a side elevation of a lighting fixture, showing my new design, and Figure 2 is a plan view looking at the under face thereof.

I claim:

The ornamental design for a lighting fixture, as shown.

In testimony whereof I affix my signature.

ALLYN B. WALTON.
